MOUNT LOADING GUIDE AND BULB
CENTERING DEVICEDaniel Mullan, Hillside, N. J., assignor to West-
inghouse Electric Corporation, East Pittsburgh,
Pa., a corporation of Pennsylvania

Application October 26, 1951, Serial No. 253,410

7 Claims. (Cl. 49—2)

1

This invention relates to sealing machines for incandescent lamps, electronic tubes and the like and, more particularly, to a mount loading guide and a bulb centering device for a sealing head on a sealing machine.

In the manufacture of incandescent electric lamps, for example, the present process of sealing the lamp mount into the glass envelope or bulb involves the manual loading of the lamp mount into the hollow mount pin of the sealing spindle or head.

The lamp mount usually comprises a coiled refractory filament mounted on a pair of leading-in conductors of a vitreous stem having an exhaust tubulation. To load the machine, the sealing operator aligns the external portions of the conductors along the tubulation and inserts the tubulation and conductors of the mount into the relatively small hole of the mount pin. The tubulation and wires must fit this hole with only a small amount of clearance to prevent mount wobble during sealing and resultant off-center mounts.

The sealing spindles or heads and, more particularly, the mount pins, rotate continuously in the path of the sealing fires at all times except in the seal molding, cooling, unloading and loading stations. The machines operate at high speed and the heads index from station to station in a matter of seconds. Thus, after a short period of operation the mount pins become extremely hot and untouchable by the operator with her bare hands.

Further, the small size of the mount pin hole and the short loading time provided by the rapid indexing of the high speed machine makes the task of loading the mounts into the sealing head a tedious and artful one. Because of these conditions, mounts are frequently erroneously loaded with one or both lead wires not within the hole in the mount pin but exposed on the outside to the sealing fires. When this occurs, the exposed lead wire or wires is burned off during sealing and mount or lamp shrinkage results which involves costly repair work or the total loss of the lamp and/or mount.

When a bulb is loaded into a bulb holder, a mount is elevated by an inclined portion of the sealing machine cam track into sealing alignment with the bulb. If the bulb is not axially aligned in the holder, the fragile filament is damaged by contact with the bulb at its opening or side walls. Further, at the rotating, sealing and cooling stations, the light bulbs tend to wobble, thereby producing crooked sealed mounts.

2

Hence, it has been found advantageous, according to my invention, to provide an automatic mount loading guide, and an automatic bulb centering device for each sealing head. My mount-loading guide functions about the pin only in the non-rotating loading stations, and then falls away from the pin prior to the bulb-loading station. My bulb-centering device, operating in co-operation with the bulb holder, locks the bulb in an axial position immediately beyond the bulb loading station, remaining locked throughout the entire sealing operation until the station immediately ahead of the position where the bulb is automatically removed from its sealing head.

15 My automatic mount guide comprises two arms, pivoted on a platform bracket connected by a link and normally separated by a coiled spring. A roller attached to one arm is provided for engagement with a cam track having inclined ends adjacent the unloading and loading stations. Engagement of the roller on this track closes the pivoted arms above the mount pin, thus providing an inverted conical guide for the convenient, accurate and rapid insertion of the mount tubulation into the pin. Its location directly above the mount pin insures an axially straight mount on the pin.

20 My bulb-centering device comprises a pair of bulb centering arms rotatable horizontally by a pair of spur gears, the driver gear of which is pinned to a vertically pivoted arm having a roller on its upper end for engagement with a cam track and a recovery counterweight affixed thereto by a counterweight arm.

25 In its general aspect, the present invention has the object of overcoming the afore-mentioned disadvantages of the prior art manual loading of mounts into sealing heads.

30 Specifically, an object of the present invention is the elimination of operator contact with the heated mount pins of an automatic sealing machine head during the mount loading operation.

35 Another and specific object of the invention is the elimination of the insertion into the mount pin of an automatic sealing machine head of mounts having lead wires exposed to the sealing fires.

40 Still another object of the invention is to provide an automatic guide on an automatic sealing machine head for the accurate and rapid insertion of the mount into the relatively small hole of the mount pin.

45 A further object is an automatic pin guide for an automatic sealing machine head which will 50 function as a guide at the non-rotating loading

stations and then fall away from the sealing pin prior to its arrival at the bulb loading station.

A still further object is an automatic mount pin guide for an automatic sealing machine head comprising two arms pivoted on a platform bracket, joined by a connecting link, normally separated by a coiled spring, and provided with a closing mechanism engageable with a spring-tensioned track behind the unloading and loading positions.

Another object is an automatic bulb centering device for an automatic sealing machine head which locks the bulb axially and eliminates filament distortion during the mount elevation into and alignment within the bulb.

An additional object is an automatic bulb-centering device for an automatic sealing machine head which eliminates bulb wobble in the rotating, sealing and cooling stations of an automatic sealing machine.

Another object is an automatic bulb-centering device, which cooperates with a sealing head bulb holder and locks the bulb in an axial position immediately beyond the bulb loading station, remaining locked throughout the entire sealing operation until arrival at the station immediately ahead of the unloading station.

A further object is a bulb centering device for an automatic sealing machine head comprising horizontally pivoted bulb centering arms operable by a pair of spur gears, the drive gear of which is pinned to a vertically pivoted roller arm having a roller for engagement on an upper cam track and a recovery counterweight affixed thereto.

Other objects and advantages of my invention will appear to those skilled in the art to which it appertains as the description thereof proceeds, both by direct recitation thereof and by implication from the context.

Referring to the accompanying drawings, in which like numerals of reference indicate similar parts throughout the several views:

Fig. 1 is an elevational view of an automatic sealing machine head at a loading station and embodying an automatic mount-loading guide and an automatic bulb-centering device of my invention;

Fig. 2 is a side elevation sectional view of a sealing head at a loading station of an automatic sealing machine, on the line II--II of Fig. 1, in the direction of the arrows;

Fig. 3 is a diagrammatic plan view of an automatic sealing machine;

Fig. 4 is a side elevational view of a sealing head showing details to illustrate the operation of the automatic mount loading guide;

Fig. 5 is a horizontal sectional view of the head at the loading station of the sealing machine on the line V--V of Fig. 4, in the direction of the arrows;

Fig. 6 is a plan view of the automatic bulb centering device of the automatic sealing machine;

Fig. 7 is a side elevational view of a lamp bulb locked axially by the automatic bulb centering device in a bulb holder, and a mount on the sealing pin in the first rotating sealing station of the automatic sealing machine;

Fig. 8 is a side elevational view of a sealed miniature lamp.

Referring to the drawings in detail, and particularly to Fig. 3, a machine for sealing tubulation and lead-carrying mounts to bulbs of evacuated electrical devices such as incandescent

lamps, electronic tubes and the like, in this showing having 16 heads, is designated by the reference numeral 10. Each of the 16 sealing heads 12, only one of which is shown in Fig. 1, is mounted on the indexing table or conveyor 14 of machine 10, and moved thereby and indexed at stations. Each comprises a sealing pin shaft assembly 16, rotatably mounted with respect to said table 14, a bulb support assembly 18, an automatic mount loading guide 22 of my invention and an automatic bulb centering device 24, also of my invention and both on said assembly 18.

Sealing pin shaft assembly

15 This lower shaft assembly 16, as shown in Fig. 1, comprises a rotatable slidable sealing pin shaft 26, a hollow shaft housing 28 of generally T-shaped vertical section, about the shaft 26, and means for rotating said head 12, such as a rotatable pulley 30, affixed to the lower extremity of the housing 28 and abutting the underside of a bearing portion of table 14. This hollow shaft 26 is slidable within an upper bushing 32 and a lower bushing 33 in housing 28. Its bottom extremity is threaded to receive a hardened cam track cap 34, slidable on a means for reciprocating each assembly 16, such as sealing machine cam track 38. The shaft 26 is provided with a longitudinal keyway 39, the length of which is greater than the combined axial length of the bearing of table 14 and the desired vertical travel of shaft 26 as shown in Fig. 1. On its upper extremity is mounted a hollow sealing pin 40 for receiving leads 50 and 51 and a tubulation 52 of a mount 45. Said pin has an upwardly flared opening 41 (Fig. 4), to a lead wire and tubulation hole 42 therein defined by a frusto-conical upper edge portion 43 to fit the inner flared surface of the stem 44 of a mount 45.

the upper extremities of rods 68 and 70, and has, as shown in Fig. 6, three bulb holder fingers 78, 80 and 82 disposed in spaced circular arrangement and shaped to supportingly engage a bulb 84.

Mount loading guide

The automatic mount-loading guide 22, as shown particularly in Figs. 4 and 5, has a pair of separable mount guide members or levers, namely a lever or arm 86 and lever or arm 88. These levers are movable to overlie sealing pin 40 for directing the leads 50 and 51 and the tubulation 52 of mount 45 thereinto during loading. The latter lever 88 is of bellcrank formation with a cam track roller 92 pivoted on the end of its generally-horizontal portion 90.

The levers 86 and 88 are pivotally mounted on a platform bracket 94 about sealing head guide rods 68 and 70, said levers being connected together by a link 96 for causing them to simultaneously move toward and away from one another and normally held apart by a coiled spring 98. Means, such as a spring-tensioned cam track 100 adjacent the unloading and loading stations of machine 10, is provided for moving said levers 86 and 88 toward one another. Platform bracket 94 (Fig. 5) is generally U-shaped in plan with side portions 102 and 104 of greater width than the intermediate portion 106.

In side portion 102 of bracket 94 (Fig. 5), there is provided a hole 108 for sealing head guide rod 68 and there is provided a mount guide arm pivot slot 110 in its forward face for receiving the mount arm 86 and limiting the pivotable motion thereof. There is a similar hole 112 in side portion 104 for rod 70. The bracket 94 is supported on and affixed, as by bolts, to blocks 116 and 118 (Fig. 4), secured to rods 68 and 70 respectively by set screws 120 and 122.

The lever 86 is desirably of rectangular cross section, as shown in Figs. 4 and 5, and has an upper inwardly projecting mount guide finger 124 with an inverted semi-conical pocket 125 for receiving and supporting the flare of stem 44. It pivots within the limits imposed by the side walls of slot 110 in bracket 94 on a fulcrum pin 126 extending through a hole 127 in arm 86. The lower extremity of lever 86 is pivotally secured to the link 96 by a pin 128 below its pivot.

Lever 88, also shown in Figs. 4 and 5, has a mount guide finger 129 with a semi-conical flare-supporting pocket 130, complementary to finger 124 and pocket 125 of lever 86. Lever 88 pivots on a fulcrum pin 131 (Fig. 5) extending through a hole 132 in arm 88 and into the rear face of side portion 104 of bracket 94. Link 96 is secured to lever 88 by a pin 133 located a distance above pivot pin 131 equal to the distance between pins 126 and 128.

The horizontal lever portion 90 of the lever 88 (Figs. 4 and 5) extends diagonally inward from the pivot point of lever 88 and then radially inward toward the center of machine 10, to permit roller 92 to follow the circular cam track 100. From the rearward side of extension 90, a coiled spring support rod 134 extends horizontally and then vertically downward. One end of coiled spring 98 is affixed to its lower extremity. The other end of spring 98 is secured in the lower end of a rod 136 depending vertically downward from the rearward portion of block 116.

The cam track 100, shown in detail in Figs. 1, 2 and 5, is a circularly arranged segment having inclined ends (Fig. 1). It is located inwardly of the sealing heads 12 (Fig. 3) at the unload-

ing and loading stations of machine 10. Each end is permanently attached by a bolt 138 and a nut 139 to an angular clip 140 of a track support assembly 141. The track is spring-tensioned by a compression spring 142 on said bolt between track 100 and the clip 140.

The track support assembly 141 comprises a pair of vertical lower track supports 144, to the lower ends of which are secured the clips 140, a horizontal angle support bracket 146 permanently attached to the machine 10, and a pair of upper track supports 148 (Fig. 1) secured to bracket 146. Each support 144 has a vertical height-adjustment slot 150 on its upper portion and is secured to bracket 146 by bolts 151 and 152 through slot 150 and nuts 153 and 154. Each upper support 148 has a similar slot 156 in its lower end and is affixed to bracket 146 adjacent support 144 by similar bolts 157 and 158 and nuts 159 and 160. Each upper support 148 has an upper horizontal lip 162 which is bolted to the extremities of a means for separating centering arms 170 and 196 of the bulb-centering device 24 during loading and unloading such as an upper cam track 164.

This cam track 164, shown in Figs. 1, 2 and 6, is a flat plate arranged similar to track 100 for engagement with a roller 166 of the bulb-centering device 24, and, as shown in Fig. 3, extends from the last cooling station, behind the unloading and mount loading stations, to the bulb loading stations of machine 10.

Bulb centering device

The bulb-centering device 24 for axially aligning bulb 84 while supported on the bulb support assembly 18, as shown in Figs. 1, 2 and 6, comprises a driver gear bulb-centering arm assembly 167 and a driven gear bulb-centering arm assembly 168, both mounted on bulb holder 72 as hereinafter explained. Assembly 167 comprises a roller arm plate 169 (Fig. 6) on the rearward portion of holder 72, the bulb-centering member or arm 170 with the bulb-centering finger 172 bolted to its forward face (as shown in Fig. 2), a drive gear 174 on said arm, a roller arm drive pin 176 projecting rearwardly from a cylindrical hub 178 on said gear, and a roller arm assembly 180 (Figs. 1 and 2) pivoted on a fulcrum pin 182 extending into the rear face of plate 169. This plate 169 is rigidly secured as by bolts to the bulb holder 72. The finger 172 of arm 170 has a V-shaped bulb-centering notch 184, as shown in Fig. 6, cut into its inner face. Arm 170, gear 174 and its hub 178 are pinned to a shaft 186 which is rotatable in plate 169. The roller arm drive pin 176 engages a longitudinal roller arm drive pin slot 188 in a roller arm 190 of roller arm assembly 180.

This roller arm assembly 180, shown particularly in Fig. 6, is for oscillating said gear 174 and to cause the centering arm 170 to periodically swing back and forth. It comprises the roller arm 190 (Figs. 1 and 2) pivoted on the pin 182 in plate 169, the cam track roller 166 on the end of arm 190, an arm 192 projecting horizontally from the roller arm 190 (Fig. 6), and a recovery counterweight 194 on the end of arm 192.

The driven gear bulb-centering arm assembly 168 comprises a mounting plate 195 (Fig. 6), similar to plate 169, a bulb-centering member or arm 196 with centering finger 198 having a notch 200, complementary to finger 172 and notch 184, a driven spur gear 202 meshing with gear 174,

and a hub 204 similar to hub 178. Arm 196, gear 202 and its hub 204 are pinned to a shaft 205 which is rotatable in plate 195.

Operation

At station 1 or 2 of the automatic sealing machine 10, as shown in Fig. 3, a mount 45 is loaded with its tubulation and leads fitting into the sealing pin 40, by means of the mount-loading guide 22, as hereinafter explained. At station 3, a bulb 84 is automatically loaded into the bulb holder 72, with the fingers 172 and 198 of assemblies 167 and 168 open, as hereinafter explained. From station 2 through station 5, the sealing pin shaft 26 and hence the mount 45 on sealing pin 40, is raised upwardly in a gradual ascent by an inclined straight portion of the sealing machine cam track 38 into sealing position with respect to bulb 84 on holder 72. At stations 5 through 12, the mount 45 and bulb 84 are rotated and sealed together to form a lamp 209 (Fig. 8) by means of stationary fires 206 and 208, shown in Fig. 7. At the seal molding station 13, sealing head 12 makes a half revolution and strikes a stop 218 (Fig. 3) thereby ceasing to rotate and permitting molding arms (not shown) to mold the seal to fit a conventional base (also not shown). At station 14 the lamp 209 rotates $\frac{1}{2}$ revolution and strikes a stop 212. Rotation of the lamp 209 ceases and cooling air is blown thereon at station 14 and at the final cooling station 15. At station 16, the sealed lamp 85 is automatically unloaded from the machine 10. Between cooling station 15 and lamp unloading station 16 and unloading station 16 and mount loading station 1, cam track 38 and hence mount pin 40 on shaft 26, drops in two steps 214 and 216, respectively (Fig. 1) to its mount loading position shown in Fig. 1.

According to my invention, when the machine indexes from the unloading station 16 to the mount loading station 1, the mount guide arm roller 92 (Figs. 4 and 5) rides up the inclined end of cam track 100, thereby bringing together the fingers 124 and 126 of mount guide arms 86 and 88. When the mount 45 is inserted between the semi-conical surfaces 125 and 130 of fingers 124 and 129, its downward descent is automatically properly guided into the hole 42 (Fig. 4) of sealing pin 40, due to the short distance between said fingers and the top of the mount pin 40. Conductors 50 and 51 are maintained in the desired alignment along tubulation 52, thereby preventing exposure of either or both of conductors 50 and 51 to sealing fires 206 and 208. As the mount leaves station 2, roller 92 rides down the inclined end of cam track 100 and the arms 86 and 88 fall backward from the axis of sealing head 12 to permit the upward motion of mount 45 on the sealing pin 40.

Further, according to my invention, as the sealing head 12 indexes from the cooling station 14 to cooling station 15, of machine 10, the bulb centering device roller 166 (Fig. 6) engages upper cam track 164, thereby forcing the roller end of arm 190 downwardly and counterweight 194 upwardly, separating fingers 172 and 198 of bulb centering arms 170 and 196. These fingers remain separated while the roller 166 is in engagement with track 164 at the unloading station 16, the mount loading stations 1 and 2 and the bulb loading station 3. Between station 3 and station 4, the roller 166 disengages itself from track 164. The counterweight 194 pulls the roller end of arm 190 upwardly to the vertical position, thereby

permitting closing of the fingers 172 and 198 about the top of bulb 84 as shown in Fig. 7. Thus the roller arm assembly 180 pinned to gear 174 by roller arm drive pin 176 rotates the gears 174 and 202 and causes said centering arms 170 and 196 to periodically swing toward one another for adjusting a bulb 84 on holder 72 at station 3 so that the mount 45, when raised, is in the correct sealing engagement therewith.

Thus, it will be seen from the foregoing description that I have eliminated operator hand contact with the hot sealing pin 40 of the sealing head 12 in the loading stations 1 and 2 of sealing machine 10 and the insertion into the mount pin 40 of mounts 45 having lead wires 50 and 51 exposed to the sealing fires 206 and 208. My automatic mount loading guide 22 for an automatic sealing machine 10 permits the accurate and rapid insertion of a mount 45 into the relatively small hole 42 of the mount pin 40. This guide 22 functions as a guide at the non-rotating mount loading stations 1 and 2 and then falls away from the sealing pin 40 prior to the bulb loading station 3. My invention has further produced an automatic bulb centering device 24 for an automatic sealing machine 10 which locks the bulb 84 axially in bulb holder 72 immediately beyond the bulb loading station 3 and eliminates filament distortion during mount elevation into and alignment within the bulb 84. This centering device 24 eliminates bulb wobble in the rotating sealing stations 5 through 13 of the automatic sealing machine 10.

While I have shown and described a specific embodiment of my invention, I am fully aware that many modifications thereof are possible, and therefore, do not intend to be restricted except as is necessitated by the scope and spirit of the appended claims.

I claim:

1. A machine for sealing tubulation and lead-carrying mounts to bulbs of evacuated electrical devices comprising a conveyor; heads on said conveyor which are moved thereby and indexed at a plurality of stations including loading and unloading stations, each head comprising a hollow sealing pin for receiving the tubulation and leads of a mount, a mount loading guide having separable guide members movable to overlie said pin for directing the tubulation and leads of a mount thereinto during loading, a bulb support assembly above said sealing pin, and a bulb centering device having separable centering members for axially aligning a bulb on said assembly; means for reciprocating each pin; means for rotating each head; means for moving together said guide members during loading; and means for separating said centering members during loading and unloading.

2. A machine for sealing tubulation and lead-carrying mounts to bulbs of evacuated electrical devices comprising a conveyor; heads on said conveyor which are moved thereby and indexed at a plurality of stations including loading and unloading stations, each head comprising a hollow sealing pin for receiving the tubulation and leads of a mount, a mount loading guide having a pair of separable guide members pivoted on said head to overlie said pin for directing the tubulation and leads of a mount thereinto during loading, said guide also having a link connecting said pair of guide members for causing them to simultaneously move toward and away from one another, a coiled spring for normally holding said members apart, at least one of said

guide members having a horizontal extension and a cam track roller on the extremity of said extension, a bulb support assembly above said sealing pin, and a bulb centering device having separable centering members for axially aligning a bulb on said assembly; means for reciprocating each pin; means for rotating each head; means for engaging said roller and for moving together said guide members during loading; and means for separating said centering members during loading and unloading.

3. A machine for sealing tubulation and lead-carrying mounts to bulbs of evacuated electrical devices comprising a conveyor; heads on said conveyor which are moved thereby and indexed at a plurality of stations including loading and unloading stations, each head comprising a hollow sealing pin for receiving the tubulation and leads of a mount, a mount loading guide having a pair of separable guide members pivoted on said head to overlie said pin for directing the tubulation and leads of a mount thereinto during loading, said guide also having a link connecting said pair of guide members for causing them to simultaneously move toward and away from one another, a coiled spring for normally holding said members apart, at least one of said guide members having a horizontal extension and a cam track roller on the extremity of said extension, a bulb support assembly above said sealing pin, a bulb centering device having a pair of separable centering members for axially aligning a bulb on said assembly, said centering device also having intermeshing gears each for carrying one of said centering members, a roller arm assembly pinned to one of said gears for rotating said gears and causing said centering members to periodically swing toward one another for adjusting a bulb on said support so that the mount when raised is in the correct sealing engagement therewith; means for reciprocating each pin; means for rotating each head; means for engaging said roller and for moving together said guide members during loading; and means for engaging said roller arm assembly and for separating said centering members during loading and unloading.

4. A machine for sealing tubulation and lead-carrying mounts to bulbs of evacuated electrical devices comprising a conveyor, heads on said conveyor which are moved thereby and indexed at a plurality of stations including loading and unloading stations, each head comprising a sealing pin shaft, a hollow sealing pin on said shaft for receiving the tubulation and leads for a mount, a mount loading guide having a pair of separable guide members pivoted on said head to overlie said pin for directing the tubulation and leads of a mount thereinto during loading, a bulb support assembly above said sealing pin, 60

a bulb centering device having separable centering members for axially aligning a bulb on said assembly, a sealing machine cam track for reciprocating each pin, a pulley on said shaft for rotating each head, a lower cam track for moving together said guide members during loading, and an upper cam track for separating said centering members during loading and unloading.

5. A head for a machine for sealing tubulation and lead-carrying mounts to bulbs of evacuated electrical devices comprising a hollow sealing pin for receiving the tubulation and leads of a mount, a mount loading guide having separable guide members movable to overlie said pin for directing the tubulation and leads of a mount thereinto during loading, a bulb support assembly above said sealing pin and a bulb centering device having separable centering members for axially aligning a bulb on said assembly.

6. A head for a machine for sealing tubulation and lead-carrying mounts to bulbs of evacuated electrical devices comprising a hollow sealing pin for receiving the tubulation and leads of a mount, 15 a mount loading guide having a pair of separable guide members pivoted on said head to overlie said pin for directing the tubulation and leads of a mount thereinto during loading, said guide also having a link connecting said guide members for causing them to simultaneously move toward and away from one another, a coiled spring for normally holding said members apart, at least one of said guide members being a bell crank having a horizontal extension and a cam track roller on the extremity of said extension; a bulb support assembly above said sealing pin, 20 and a bulb centering device having separable centering members for axially aligning a bulb on said assembly.

7. A head for a machine for sealing tubulation and lead-carrying mounts to bulbs of evacuated electrical devices comprising a hollow sealing pin for receiving the tubulation and leads of a mount, a mount loading guide having separable guide members movable to overlie said pin for directing the tubulation and leads of a mount thereinto during loading, and a bulb support assembly 25 above said sealing pin.
